INKING DEVICE FOR PRINTING MACHINES

Filed August 17, 1925

Inventor:
Harmon P. Elliott

Harmon P. Elliott

UNITED STATES PATENT OFFICE.

HARMON P. ELLIOTT, OF CAMBRIDGE, MASSACHUSETTS.

INKING DEVICE FOR PRINTING MACHINES.

Application filed August 17, 1925. Serial No. 50,880.

This invention relates to inking devices for printing machines and has for objects the provision of an ink roll adapted to contain a supply of liquid ink, and having ink-passages in a portion of its periphery, with means to maintain the roll normally in position with the ink-passages above the level of ink in the roll; and means to lower the roll into rotatable engagement with an ink-distributing roll, whereby to distribute ink on the surface of said latter roll, and thereafter to return the roll to its normal position.

A further object is generally to improve the construction and operation of inking and equivalent devices.

Fig. 1 is a detailed side elevation of the inking mechanism of a stencil printing machine embodying the invention.

Fig. 2 is a plan view of the inking device, including the ink roll, embodying the invention.

Fig. 3 is a sectional detail through one of the trunnion-supports for the ink roll, illustrating especially the eccentric rotatable support for the ink-roll.

Figs. 4 and 5 are sectional views taken along line 4-4 of Fig. 2 and illustrating respectively the inoperative and operative positions of the ink roll.

The inking device embodying the invention is well adapted for use in a stencil printing mechanism wherein the ink-roll is adapted, upon need, to deposit ink onto the periphery of roll 10, which transfers it to roll 12 and thence to roll 14, which latter roll, when depressed, operates on a stencil 16 to effect the printing operation. Ink need be applied to the surfaces of said rolls only at intervals and, consequently, the inking device is adapted normally to be supported out of contact with said roll 10.

The inking device embodying the invention includes an ink-roll comprising a hollow cylinder 20 adapted to contain a supply of liquid ink within it, which may be introduced within the roll through an opening in one of the hubs 22 which extend outwardly from the end-walls of the roll. The filler-opening may be removably closed by a screw-threaded filler-plug 24.

A portion of the circumference of said rolls is provided with a plurality of perforations 26 which extend into the interior of the cylinder and provide ink-passages through which the ink may pass to be de-

posited on the transfer or distributing roll 10. Said perforations are staggered with respect to each other as illustrated in Fig. 2, whereby to distribute ink in small drops 60 or globules uniformly over the axial length of the transfer roll 10. The perforations 26 extend over a relatively small circumferential extent of the ink roll so that they will all lie above the ink-level within the 65 ink-roll when said roll is in its normal and inoperative position, thereby to prevent ink from running out of the perforations when not desired. The roll is normally maintained with its perforations in the aforesaid 70 relation by a weight 28 which is disposed within the ink roll and secured to the side wall thereof beneath its axis and on the side opposite said perforations, whereby to unbalance the roll in a direction to maintain 75 the perforations above the ink-level, when the roll is not being rotated.

The ink-roll is adapted to be maintained normally in elevated position above and free from contact with the distributing roll 10 80 and means are provided to support it in such relation and to raise and lower it out of and into rotatable and ink-transferring engagement with said roll, upon need. Said means includes a supporting frame which comprises spaced hubs 32, arms 34 integral with said hubs and extended in the same direction outwardly toward the periphery of and over opposite end walls of said ink-roll, and a relatively massive bar 36 which is integral 85 with said arms and serves rigidly to connect said arms, and hubs, and extends axially over and is free from engagement with the periphery of said ink-roll.

Said supporting frame is extended between arms 38 of the printing machine and above the distributing roll 10, and the hubs 32 of said frame are rotatably disposed removably in slots 40 in said arms. Said frame may be retained removably in said 95 position by pins 42 which are extended across said slots 40 over said hubs and, if desired, spring-members 44 may be disposed between said hubs and pins, whereby to exert some amount of spring-pressure on the frame to 100 maintain it in the bottoms of said slots.

The ink-roll 20 is disposed within said supporting frame and is supported rotatably on trunnion-pins 46, which pins are screw-threaded removably in said hubs 32 and extend freely into axially-aligned recesses in the hubs 22 of said roll. Check-nuts 48 on

the outer ends of said pins serve to secure them in set position.

In accordance with this invention, said trunnion-pins are eccentrically disposed in the hubs 32 of said frame, or are offset from the axis of said hubs, as illustrated in Fig. 3.

The normal or unoperated position of the ink-roll and supporting frame is illustrated in Fig. 4, where the ink-roll is in raised position above the distributing roll 10, with the perforations 26 in the upper portion of the roll above the ink-level therein and with the axis of the ink roll about on the level of the axis of the supporting frame, and forwardly thereof. When ink is to be applied to the surface of the distributing roll, the frame is rotated forwardly, or in a counter-clockwise direction, Figs. 4 and 5, thereby lowering the axis of the ink-roll and moving it onto the rotating distributing roll, in which position it will be maintained by the weight of the parts. The rotation of the distributing roll causes the ink-roll to rotate in engagement therewith and to move the ink-perforations below the ink level, whereby ink will flow out of the ink-roll onto the surface of the distributing roll. When a sufficient amount of ink has been deposited on the ink-roll, the supporting frame is returned to its original position, thereby raising the ink-roll from contact with the distributing roll; and the weight 28 will support the ink-roll with the ink-perforations disposed above the ink-level.

One of the hubs 32 of the supporting frame is provided with a handle 50 whereby to reciprocate the frame to raise and lower the ink-roll. The weight of the frame, residing principally in the cross-bar 36, is disposed to hold the frame, and the ink-roll, in whatever position it may be moved. A pin 52 may extend from one of the arms 34 of the supporting frame into a position to engage with the opposite side walls of one of the notches in the arms 38 of the inking mechanism, whereby to limit the movement of the frame.

I claim:

1. An ink-roll for a printing machine comprising a hollow, ink-containing cylinder having perforations in a portion only of its periphery, means to support said cylinder for rotation about its axis, means to hold said rotatable cylinder in position with its perforations normally above the ink-level in said cylinder, and means to raise and lower said cylinder including means biasing said cylinder to remain in both raised and lowered positions.

2. An ink-roll for a printing machine comprising an eccentrically-weighted, rotatable cylinder having peripheral perforations opposite the weight, a supporting frame for said cylinder having hubs disposed at the ends of said cylinder on which the frame is rotatably supported, and trunnion-pins for

said rotatable cylinder carried eccentrically by said hubs.

3. An ink-roll for a printing machine comprising an eccentrically-weighted rotatable cylinder having peripheral perforations opposite the weight, and means to raise and lower said cylinder including a rotatably-supported frame having eccentric supporting means for said rotatable cylinder, said frame having two positions into which it may be moved, and means biasing said frame to remain in both of said positions.

4. An ink-roll for a printing machine comprising an eccentrically-weighted rotatable cylinder having peripheral perforations opposite the weight, means to raise and lower said cylinder including a rotatably-supported frame having eccentric supporting means for said rotatable cylinder, said frame having two positions into which it may be moved, and means including a weight carried by said frame arranged to hold said frame in both of said positions.

5. An ink-roll for a printing machine comprising an eccentrically-weighted rotatable cylinder having peripheral perforations opposite the weight, and means to raise and lower said cylinder including a rotatably-supported unbalanced frame having eccentric supporting means for said rotatable cylinder.

6. An ink-roll for a printing machine comprising an eccentrically-weighted rotatable cylinder having peripheral perforations opposite the weight, and means to raise and lower said cylinder including a rotatably-supported unbalanced frame having eccentric supporting means for said rotatable cylinder, and a stop-member to hold said frame in positions corresponding to raised and lowered positions of said ink-roll.

7. An inking device for a printing machine comprising a frame having spaced and aligned hubs on which the frame is rotatable and an off-set, weighted bar connecting said hubs, a rotatable ink-roll disposed between said hubs, and trunnion pins screw-threaded eccentrically in said hubs and arranged in supporting relation with said rotatable ink-roll.

8. An inking device for a printing machine comprising a frame having spaced and aligned hubs on which the frame is rotatable, which hubs extend outwardly beyond the body of said frame, and an off-set, weighted bar connecting and disposed between said hubs, and an ink-roll disposed between said hubs and rotatably supported eccentrically therebetween, said ink-roll comprising an eccentrically-weighted cylinder having peripheral perforations opposite the weight.

9. An inking device for a printing machine comprising an eccentrically-weighted rotatable cylinder having peripheral perforations

rations opposite the weight, means to raise and lower said cylinder and means urging said cylinder for movement toward the raised position thereof.

5 10. An inking device for a printing machine comprising a pair of spaced arms having opposed open slots therein, a frame having hubs journalled in said slots and having an offset bar connecting, and extended upwardly from, said hubs, means to reciprocate said frame, and an ink-roll pivotally mounted eccentrically in said frame between said hubs.

10 15. An inking device for a printing machine comprising a pair of spaced arms having opposed slots therein, a frame having hubs journalled in said slots and having an offset bar connecting, and extended upwardly from, said hubs, means to reciprocate said frame, means to retain said frame removably in said arms including pins extended transversely across said slots, spring-members disposed between said pins and

hubs and bearing against both, and an ink-roll pivotally-mounted eccentrically in said frame between said hubs.

12. An inking device for a printing machine comprising a pair of spaced arms having opposed slots therein, a frame having hubs journalled in said slots and having an offset bar connecting and extended upwardly from said hubs, means to reciprocate said frame, means to retain said frame removably in said arms including pins extended transversely across said slots, spring-members disposed between said pins and hubs and bearing against both, and an ink-roll pivotally mounted eccentrically in said frame between said hubs, said ink-roll comprising an eccentrically-weighted rotatable cylinder having peripheral ink-passages opposite the weight.

In testimony whereof, I have signed my name to this specification.

HARMON P. ELLIOTT
